COMBINATION HOUSE AND CAMPING TRAILER

Walter Bird, Costa Mesa, Calif., assignor to William S. Correll, Costa Mesa, Calif.

Application April 12, 1956, Serial No. 41,044

Term of patent 14 years

(Cl. D14—3)

Figure 1 is a perspective view of the combination house and camping trailer, embodying my new design;

The side of the trailer illustrated in Figure 3 is identical, except for door and window structures, with the side illustrated in Figure 1. Accordingly, the sections shown in Figures 5—8 are equally applicable to the side of the trailer shown in Figure 1.

I claim:

The ornamental design for a combination house and camping trailer, substantially as shown and described.
